UNITED STATES PATENT OFFICE.

HAROLD S. BLAKE; OF ATTLEBORO, MASSACHUSETTS.

GAS CONTROL FOR OIL BURNERS.

Application filed August 4, 1926. Serial No. 127,047.

This invention relates to improvements in liquid-fuel burning apparatus of the on-and-off type; and has for its object to provide in such an apparatus means for electrically controlling the flow of gas to the pilot light, whereby when a mixture of air and oil are forced into the furnace after a rest period the flow of gas to the pilot light is simultaneously and automatically increased in volume and for a sufficient period to fully ignite the fuel mixture after which this large flow is reduced to the minimum or sufficient to just feed a small jet, where it remains during the remainder of that heating period and until again called upon to ignite another initial charge after the apparatus has had another rest period.

A further object of the invention is the provision of electromagnetic means in the electric circuit, which is deenergized at the time the power is shut off to arrest the air blower and the flow of oil, which deenergizing action serves to close one valve in the main gas supply and open another valve therein, and when the heating apparatus is again started after a period of rest, this electromagnet is energized to promptly open the closed valve and effect a delayed closing of the open valve during which interval of delay a full charge of gas is supplied to the pilot sufficient to fully ignite the initial charge of fuel being forced into the furnace, a bypass or auxiliary supply pipe being provided for continuing a sufficient supply to the jet to prevent it from being completely extinguished.

The invention further consists in the provision of electromagnetic means for opening and closing the oil supply control valve simultaneously with the starting of the blower when the circuit is again closed.

With these and other objects in view, the invention consists of certain novel features of construction, as will be more fully described, and particularly pointed out in the appended claims.

In the accompanying drawings:

Figure 1 is a side elevation illustrating the general arrangement of my improved heating apparatus and showing one arrangement of supply pipes for the air, oil and gas.

Figure 2 is a perspective view illustrating the electromagnetic means for controlling the flow of the gas and the oil.

Figure 3 is a sectional elevation illustrat-

ing the resistance unit which causes a delayed closing of one of the gas valves.

Figure 4 is a sectional elevation showing the electromagnet for controlling the action of the oil supply valve.

Figure 5 is a diagrammatic view illustrating the general wiring diagram by which the different units are connected in the circuit to operate when the circuit is opened and closed.

Figure 6 is a sectional view showing the two control valves in the main gas supply, one being shown as open and the other closed.

It is found in the practical operation of liquid fuel burning apparatus of the alternate off and on type for heating systems as applied to furnaces where a pressure of air is mixed with oil and the mixture forced into a furnace for a heating period and then shut off for a rest period, of advantage to provide a gas flame of sufficient volume to quickly ignite this fuel mixture at the time it is initially forced into the furnace after each period of rest and to provide a pilot light of sufficient volume to ignite this mixture without being extinguished; also after the mixture has been properly ignited to then reduce the flow of the gas to the pilot light to the very minimum permitting the pilot jet to remain lighted, whereby it is maintained ready to be again increased to ignite the next fuel mixture after a rest period; and in order to provide simple and effective means for so controlling this gas flow, I have provided a main and an auxiliary gas supply pipe, the auxiliary pipe being for the purpose of continuously supplying the pilot with the minimum amount of gas, when the main is shut off, the main pipe being for the purpose of permitting a large volume of flow for a limited period during the initial igniting of the charge of fresh fuel.

In this main line, I have mounted a pair of valves both of which are connected to an electromagnet, whereby when the magnet is deenergized the fall of the magnet core by gravity will close one of the valves by completing the circuit, it will first act upon the closed valve to open it and also acts upon the open valve to effect a delayed closing thereof, whereby for a short period a large volume of gas is permitted to flow to the pilot to well ignite the fresh charge of fuel, after which the closing of the last valve shuts off the supply through

the main, permitting the small supply through the bypass or auxiliary pipe to supply the gas pilot jet by which arrangement of apparatus the larger volume of gas is used 5 only for a very short time to reduce the operating expense; and the following is a detailed description of the present embodiment of my invention and showing one means by which these advantageous results

10 may be accomplished:—

With reference to the drawings, 10 designates the deflector member located in the furnace 11, and 12 designates the air supply tube, one end 13 of which is located in the 15 furnace, while the other end is connected to the blower 14 which causes a forced draft of air thereinto.

The oil is supplied from an auxiliary tank 15 to flow by gravity by way of the pipe 16 20 through an oil control valve 17 which is operated by an electrical magnet 17^a and from this valve passes by way of pipe 18 through the base 19 of the blower and through the tube 12 to the discharge end 25 thereof to mix with the air flowing from this tube and be forced against the deflecting member 10 in the furnace. The gas for supplying the pilot light which initially ignites this fuel mixture enters from any 30 convenient source through a pipe 20 and main pipe 21, which latter pipe is provided with a pair of valves 22 and 23, and a bypass or auxiliary pipe 24 is also provided in which is located a manually operable control valve 25 to continuously supply a small 35 quantity of gas to the pilot jet 26.

It is found in practice of advantage to initially inject a comparatively large jet or flame into the fuel mixture 27 of air and oil 40 as it is forced from the end 13 of the tube 12 after each rest period.

In order to control the period of increased gas flow, I have mounted an electromagnet 28 in the electric circuit 29; see Figure 5. 45 The core 30 of this electromagnet is connected to the valve 22 through the arm 33, rod 34 and valve lever 35 and this electromagnet is operatively connected to the valve 23 through the resistance unit 36 which comprises a chamber 37 filled with glycerine and 50 in this chamber is mounted a disc 38 which rests upon its seat 39, the disc being provided with a stem 40 extending out through the end 41 of the chamber, and it is connected to the solenoid core 30 by a spring 42, also this solenoid core is provided with a resilient arm 43 which is arranged to engage the arm 44 on the stem 40 so that when the magnet is deenergized the core will drop 55 by gravity and this member 43 will act through the arm 44 and connecting rod 45 upon the lever 46 to move the valve 23, to open position, which may be effected either by a manual opening of the main switch 47 60 in the circuit or by action of the thermostat

48 which may be set in any of the rooms to be heated, or by action of the pressurestat 48 which may be effected by the steam pressure in the furnace, which opening of the circuit also shuts off with the blower motor 70 50.

The electromagnetic oil control valve 17 is simultaneously deenergized to shut off the supply of oil.

When the circuit is now closed either by 75 action of the thermostat or pressurestat, the fan motor is started and the electromagnetic valve 17 controlling the oil supply is opened and at the same time the electromagnet 28 is energized which serves to lift its core 30 80 to at once open the gas valve 22 in the main; by this action it will be seen that both the valve 22 and the valve 23 are now open to permit a free flow of a large volume of gas to the pilot sufficient to ignite the initial fuel 85 mixture as it is forced into the furnace, which large flame is maintained for a short period, and this upward movement of the solenoid core 30 also effects a deferred closing movement to the now open valve 23, 90 which is accomplished through the resistance unit 36 above described by exerting a tension on the spring 42 which serves to slowly lift this disc 38 from its seat 39 where it is held by suction after a predetermined 95 period to break the vacuum thereunder and permit the valve 23 to be moved to closed position and so shut off this maximum volume of gas to the pilot.

This cycle of operations is repeated each 100 time the circuit is opened and closed to de-energize and energize the electromagnet to open and close the main gas valves; first to supply the pilot with a large flame sufficient to ignite the fuel supply and later shut off 105 the igniting flame until again called upon to initially ignite another charge after each rest period.

The foregoing description is directed 110 solely towards the construction illustrated, but I desire it to be understood that I reserve the privilege of resorting to all the mechanical changes to which the device is susceptible, the invention being defined and limited only by the terms of the appended 115 claims.

I claim:

1. In a liquid fuel burner, an electric circuit, separately actuated means in the circuit for supplying air and oil to the burner, main and auxiliary conduits for supplying gas for fuel ignition, a normally closed and a normally open valve in said main, electromagnetic means for first opening said closed valve, and a resistance unit interposed between said open valve and said electromagnetic means for controlling a subsequent closing of this second valve after a predetermined open period.

2. In a liquid fuel burner, an electric cir-

cuit, means in said circuit for controlling the supply of air and oil to the burner, main and auxiliary conduits for supplying gas for igniting the fuel supply, a pair of valves in 5 said main, electromagnetic means in said circuit for closing one of said valves and opening the other when deenergized, and for promptly opening the closed valve and effecting a delayed closing of the open valve when 10 energized.

3. In a liquid fuel burner, a blower for supplying a draft of air to the burner, a pilot jet, a gas conduit for supplying gas to the pilot, an electric circuit, a blower motor 15 in said circuit, and means in said circuit operated simultaneously with the starting of said motor for increasing the gas flow to the pilot jet and means mechanically connected to the first said means and directly actuated 20 thereby for subsequently decreasing this gas flow to the pilot at the end of a predetermined period.

4. In a liquid fuel burner, a gas pilot jet, a conduit for supplying gas thereto, a pair 25 of valves in said conduit, electrically actuated means for operating one of said valves, and means mechanically connected to said actuating means and directly responsive to the action thereof for operating the second 30 valve at the end of a predetermined period of time.

5. In a liquid fuel burner, a gas pilot jet, a conduit for supplying gas thereto, a pair 35 of valves in said conduit, electrically actuated means for operating one of said valves, a spring connected to said actuating means and to said other or second valve for operating the same, and a mechanical resistance connected to said other or second valve for 40 retarding the action thereof whereby said second valve operates at a later period than the first valve.

6. In a liquid fuel burner, a gas pilot jet a conduit for supplying gas thereto, a pair 45 of valves in said conduit, electrically actuated means for operating one of said valves, a chamber, a plate in said chamber, a second plate in contact with the first plate, a piston rod carried by the second plate, liquid in said chamber about said plates, means connecting 50 said piston rod and second valve, and a spring connecting said electrically actuated means and piston rod through which a pull is exerted on said piston rod, the same being retarded in its movement by means of suction 55 between said plates.

7. In a liquid fuel burner, a gas pilot jet, a gas conduit connected thereto, an oil jet, an oil conduit thereto, a valve in the conduit, a blower, an electric circuit, electrically 60 operated means for starting said blower and opening the oil valve and means simultaneously operated by said electrical circuit for increasing the gas pilot flow upon the starting of the blower and means mechanically 65 connected to the gas pilot increasing means and directly actuated thereby for shutting down the gas pilot flow at the end of a predetermined period of time.

8. In a liquid fuel burner, a gas pilot jet, 70 a conduit for supplying gas thereto, a pair of valves in said conduit, one open and the other closed when the burner is inoperative, means for opening the closed valve, means 75 mechanically directly connected to said valve opening means and actuated thereby for closing the other or open valve at the end of a predetermined length of time, and a bypass conduit leading around said valves by which 80 a predetermined minimum quantity of gas may continuously flow to said pilot jet.

In testimony whereof I affix my signature.

HAROLD S. BLAKE.
